LOCKING WEDGE FOR FREEZER DIVIDERS

Edmund J. Buzicky, St. Paul, Minn., assignor, by mesne assignments, to Whirlpool Corporation, a corporation of Delaware

Application May 28, 1954, Serial No. 433,191

10 Claims. (Cl. 220—22)

This invention relates to a packing wedge for freezer dividers and deals with a means of holding freezer dividers in an adjusted position.

In order to segregate one type of goods within a freezer from another, freezer dividers are often used. These dividers act to divide the floor space into sections so that articles of one type may be placed in one portion of the freezer and goods of another may be placed in another portion. In view of the fact that the articles contained are often of considerable weight, some difficulty is experienced in securing these dividers in an adjusted position. It will be understood that the inner surfaces of the freezers are usually smooth and unbroken and are normally not provided with cracks or slides which hold the dividers in a proper position.

The present invention resides in the provision of a locking wedge capable of holding freezer dividers in any adjusted position. Through the use of these wedges, the tops of the partitions are securely locked in place and the dividers are held from lateral movement. At the same time, the partitions may be easily removed and the locking wedges unlocked when it is desired to do so.

A feature of the present invention lies in the provision of a divider or partition wall for a chest type freezer having an inclined track secured thereto near the upper extremity thereof. Preferably, one such track is provided on each side of the divider at the top thereof. Wedges formed of rubber or resilient plastic are slidably supported upon these tracks, the tracks inclining downwardly and outwardly toward the freezer walls. By pressing downwardly on the wedges, the bottom of the partition or divider is urged against the bottom of the freezer compartment and the wedges lock the partition from lateral movement. As a result, articles of considerable weight may be stored on one side of the divider without moving the same or causing the locking wedges to loosen.

A further feature of the present invention lies in the fact that the locking wedges may be easily pulled upwardly when it is desired to unlock them from their locked position. When the wedges are pulled upwardly, the partition is released and it can be lifted from the freezer chest by merely lifting upwardly upon the wedges, the upper sliding movement of the wedges being limited.

These and other objects and novel features of my invention will be more clearly and fully set forth in the following specification and claims.

In the drawings forming a part of the specification:

Figure 1 is a side elevational view of a portion of a partition showing this partition or divider locked in position between the walls of a freezing chest or the like.

Figure 2 is a top plan view of one of the locking wedges in place upon the partition or divider.

Figure 3 is a perspective view of one of the wedges removed from the divider.

Figure 4 is a sectional view through the locking wedge, the position of the section being indicated by the line 4—4 of Figure 1.

2

Figure 5 is a sectional diagrammatically through a freezer showing the general manner in which the partition is inserted.

As is indicated in Figure 5 of the drawings, the freezer 5 A includes an interliner having opposed liner walls 10 and 11 a bottom liner wall 12. These liner walls are in spaced relation to casing walls 13 which form the freezer casing. Insulation 14 is positioned between the liner walls and the outer casing so as to prevent the travel of heat into the freezer.

The partition is best illustrated in general by the letter B. The partition is shown as having vertical side frame members 15 and 16 which are connected along their lower ends by a cross connecting member 17. The upper ends of the sides 15 and 16 incline upwardly and inwardly as indicated at 19 and 20 respectively. A cross connecting member 21 connects the upper ends of the inclined members 19 and 20, completing the generally rectangular outer frame.

Vertical frame members 22 are provided extending between the top and bottom of the frame and laterally extending cross members 23 extend between opposite sides of the frame. Feet 24 of rubber or other suitable material may be provided to rest against the bottom 12 of the liner so as to prevent slippage of the bottom of the partition member.

With reference now to Figure 1 of the drawings, it will be noted that a flat strip 25 extends along, and is secured to, the outer surface of the inclined portions 19 and 20 of the frame. The tracks 25 extend on either side of the partitions so as to slidably support the wedges which will be described. The lower end of the strip 25 is turned vertically as indicated at 26 to resist downward movement of the locking wedges beyond a certain point. The upper end 27 of the strip is bent at right angles to the body of the strip so as to act as a stop to limit upward movement of each wedge. As both of the wedges are identical and as the manner of supporting the wedges on both sides of the freezer is identical, only one wedge is shown in Figure 1.

The wedges are illustrated in general by the letter C and are formed as best illustrated in Figures 3 and 4 of the drawings. Each wedge includes a body of resilient material having a bottom end 29 and a right angularly extending vertical edge 30. The vertical edge 30 is rounded or curved at 31 to form a flat top 32 which is parallel to the bottom 29. The fourth side 33 of each wedge C converges toward the side 30 thereof, the angles of the convergence being similar to the angles at which the track or strip 25 assumes with respect to the vertical.

As is best indicated in Figure 3 of the drawings, the side 33 is provided with a longitudinally extending groove 34 extending throughout its length, this groove 34 being of proper width to accommodate the strip 25. Each side 33 is also provided with a pair of inwardly directed opposed flanges 35 and 36 which overlie the groove 34 and extend parallel to the base of the groove. These flanges 35 and 36 are spaced apart a distance sufficient to accommodate the frame portion 19 of the divider frame therebetween.

Each side of the wedge shaped body is provided with a recess 37 therein, the recess being rounded and for the sake of appearance, generally similar in shape to the outer shape of a wedge. These recesses are designed to accommodate the fingers so that the wedges may be lifted by engagement with the fingers.

The wedges C are inserted upon the track 25 at the lower end thereof, the flanges 35 and 36 flexing sufficiently to permit the wedges to manipulate the bend between the main body of the strip and the end 26 thereof.

However, in view of the fact that the flanges must flex considerably in order to apply the wedges, the wedges will not become detached accidentally. As a result, the bent lower end 26 of the track 25 resists downward movement of the wedge below the point of bend. The angularly turned track end 27 engages the wedge flanges 35 and 36, limiting upward movement of the wedge. As an alternative method of manufacture, the end 26 of each strip may be bent after the wedges are slidably supported thereupon.

Once the divider has been formed and equipped with wedges C on either side thereof near the top, it is possible to insert the divider in the freezing compartment in any desired location. The divider is placed in the desired position and a downward force is exerted upon the tops of the wedges. This action causes the wedges to slide downwardly forcing the outer surfaces of the wedges against the liner walls and somewhat compressing the bodies of the wedges. Once these wedges are forced into place, the top of the partition is securely locked in place. During this action, the lower end of the divider has been pressed against the bottom of the liner and, accordingly, the bottom of the divider is held in place. Either the rubber legs 24 or laterally extending legs may assist in this purpose.

When it is desired to remove the divider or to change the position thereof, it is only necessary to grasp each wedge between the thumb and forefinger of a hand and to raise the wedges upwardly. This action withdraws them from their contact with the wall and permits the entire divider to be lifted from the freezer chest or to be adjusted in position.

I have found that if the wedges are formed of somewhat resilient material, they will accomplish their intended purpose over a considerable period of time. The locking and unlocking of the wedges is extremely simple in form and in action and requires but little force in operation.

In accordance with the patent statutes, the principles of construction and operation of locking wedge for freezer dividers have been described and while it has been endeavored to set forth the best embodiments thereof, it is desired to have it understood that obvious changes may be made within the scope of the following claims without departing from the spirit of the present invention.

I claim:

1. A divider for chest type freezers including a partition wall, inclined track means supported near the upper extremity of said wall, said inclined track means sloping downwardly and outwardly and said partition wall having means secured to the track means and maintaining the inclination thereof, and wedge-shaped members slidably supported on said inclined track means and slidably engageable against the walls of the freezer upon downward movement thereof to bear by wedging force between said inclined track means and the freezer walls to hold said divider in locked position.

2. The construction described in claim 1 and in which the partition walls are foraminous.

3. The construction described in claim 1 and in which the wedges are formed of resilient material.

4. The construction described in claim 1 and in which the wedges are formed of resilient compressible material and are compressed by downward movement between the supporting tracks and the freezer walls to mount said divider in said freezer.

10 5. A divider for use in chest type freezers including a divider frame, a pair of inclined tracks supported by said frame near the upper end thereof, said tracks inclining downwardly and outwardly toward the freezer walls, a wedge shaped element having a vertical wall and an inclined wall slidably mounted on each of said inclined tracks, said wedge shaped element being operable, upon downward movement of the same, to be wedged between its supporting inclined tracks and an adjacent vertical wall of the freezer.

15 20 6. The construction described in claim 5 and in which said wedges are formed of resilient compressible material.

7. The construction described in claim 5 and in which the wedges include oppositely disposed recesses in opposite sides thereof designed to accommodate the fingers for lifting the wedges.

25 8. The construction described in claim 5 and including means at the end of said inclined tracks for limiting the sliding movement of said wedges on said tracks in both directions.

30 35 40 9. A divider for chest type freezers including a frame designed to extend transversely of the freezer chest having the uppermost ends of its sides inclining upwardly and inwardly, a pair of inclined strips supported near the upper end of said divider, said strips inclining downwardly and outwardly toward opposite walls of the freezer chest in conformance with the inclination of said frame sides, a wedged shaped body overlying each of said strips and having a wall with the angle of convergence similar to the angle of the said strip incline, and inclined flanges extending over said strips and supported upon said body for slidably supporting said body upon each said strip, whereby downward sliding movement of each wedged shaped body upon its supporting strip acts to wedge said body between its said supporting strip and the adjacent freezer wall.

45 50 55 10. The construction described in claim 9 and in which said wedged shaped bodies are formed of resilient compressible material.
